GUN FEEDING MECHANISM

Filed March 26, 1928

INVENTOR
Louis S. Marsh

UNITED STATES PATENT OFFICE

LOUIS S. MARSH, OF SEATTLE, WASHINGTON, ASSIGNOR TO BOEING AIRPLANE COMPANY, OF SEATTLE, WASHINGTON

GUN-FEEDING MECHANISM

Application filed March 26, 1928. Serial No. 264,722.

This invention relates to improvements in gun feeding mechanisms, and more particularly to airplane armament of the machine gun type, and has for its principal object to 5 provide a mechanism whereby a quantity of ammunition may be fed to a gun or guns from cartridge spools or reel members, the rotation of which is caused by the gun drawing the bullets into the breach. The rotation of 10 the cartridge spools or reel is automatically governed by brake shoes, which operate from the triggers, or firing controls. In other words, every time the trigger is pulled, the brake is momentarily lifted from the reel 15 to permit advancement of the bullets, and immediately upon release of the trigger, the brake shoe grips the cartridge spool, thus preventing the spool from over-running, with a resultant unwinding of the cartridge belt. 20 These and other objects will appear as my invention is more fully hereinafter described in the following specifications, illustrated in the accompanying drawings, and finally pointed out in the appended claims.

25 In the drawings—

Figure 1, is a fragmentary side elevation of an airplane fuselage, showing a machine gun mounted thereon, with my improved form of bullet feeding spools or reel members and braking device in operative engagement therewith.

Figure 2, is a reduced end elevation of Figure 1 looking in the direction of the arrow in Figure 1, with some parts omitted for convenience in illustration.

Figure 3, is an enlarged side elevation of my improved form of brake member in contact with the periphery of one of the reel members.

40 Figure 4, is an edgewise view of the brake member.

Referring now more particularly to the drawings—

Reference numeral 1 indicates the fuselage 45 of an airplane, of usual steel tubing construction, having the usual control stick 2 swingably mounted within the fuselage, and within convenient reach of the operator. 3 indicates generally a machine gun of any approved 50 type, mounted to the fuselage, 1, and adapted

to receive its ammunition in belt formation, as at 4, from a cartridge reel 5. A reel is provided for each gun, and each is rotatably mounted within a shaft 6, and suitable brackets 7.

Near the upper end of the control stick 2, and in the proximity of the handle portion thereof, are mounted gun controls or triggers 8, from which extend control cables 9, through suitable flexible tubular housing. 60 The cables extend to the usual trigger mechanism, on the gun. 10 indicates a similar pair of cables, spliced to the cables 9 and extending upwardly to the brake members 11, so that, as the triggers on the stick 2 are moved, inwardly and outwardly, a corresponding reciprocal movement will be imparted to both sets of cables, 9 and 10, and simultaneously to the brake members, thus, with each operation of the trigger, the corresponding reel will be 70 free to rotate in its feeding operation. The brake member consists of a hollow main body member 12, embracing near its upper end, a tubular housing 13, for a spring member 14, one end of which spring is secured to an arm 16, which is made integral with a bracket 17 and which bracket is welded to the fuselage, 1, and which pivotally supports the main body 12 of the brake member. A brake shoe 18, of any suitable resilient material, is 80 removably secured within the main body member 12. The brake body and the brake shoe are of such shape as to become tangentially disposed to the periphery of the cartridge reel, when the brake is applied, thus causing 85 a wedging action, and instantaneous stopping of the reel.

While I have shown a particular form of embodiment of my invention, I am aware that many minor changes therein will readily suggest themselves to others skilled in the art, without departing from the spirit and scope of my invention.

Having thus described my invention what I claim as new and desire to protect by Letters Patent, is:

1. In apparatus of the class described, the combination of a cartridge reel, cartridges adapted to be drawn therefrom in belt-like formation, means operable simultaneously 100

with the trigger of a machine gun for intermittently arresting the feeding action of said cartridge reel, said arresting occurring immediately after the firing of the gun.

5 2. In apparatus of the class described, the combination of a reel, cartridges adapted to be drawn therefrom in belt-like formation means operable simultaneously and automatically with the operation of the trigger of a machine gun for intermittently arresting
10 10 said rotation of said reel member.

15 3. In apparatus of the class described, the combination of a cartridge reel, cartridges adapted to be drawn therefrom in belt-like formation, means operable simultaneously and automatically with the operation of the trigger of a machine gun for intermittently arresting the rotation of said reel member, said means comprising a brake shoe resiliently mounted for engagement with the periphery of one of the reel flanges.

20 4. In apparatus of the class described, the combination of a cartridge reel in conjunction with a machine gun, means operable by
25 the gun firing controls for arresting the rotation of said cartridge reel after each firing of the gun, said means comprising a yieldingly mounted brake member having a resilient surface adapted for wiping and wedging
30 contact with the cartridge reel, and a flexible connection between said brake member and said gun controls.

In testimony whereof I affix my signature.
LOUIS S. MARSH.
